UNITED STATES PATENT OFFICE.

LEVI A. BEARDSLEY, OF SOUTH EDMESTON, NEW YORK.

MACHINE FOR REMOVING BARK FROM WILLOWS, &c.

Specification of Letters Patent No. 28,824, dated June 26, 1860.

To all whom it may concern:

Be it known that I, LEVI A. BEARDSLEY, of South Edmeston, in the county of Otsego and State of New York, have invented certain new and useful Improvements in Machines for Removing the Bark from Willow or other Twigs; and I do hereby declare that the following is a full, clear, and exact description of the same, reference being had to the accompanying drawings, making part of this specification, in which—

Figure 1 is a perspective view of the machine complete, as seen from in front, but with a portion of the jaw i^2 removed. Fig. 15 2 is a perspective view of the machine, as seen from the driving end, but with the feeding carriage removed. Fig. 3 is a vertical section of the machine taken near the upright frame E' . Fig. 4 is a perspective 20 view of the feeding carriage. Fig. 5, is a perspective view of the upper rubbing slab, reversed. Fig. 6, is a perspective view of the frame of the upper rubbing slab. Fig. 7, is a perspective view of one of the blocks 25 (7) contained in the upper rubbing slab, and Fig. 8, is a perspective view of the lower rubbing slab, reversed.

Similar characters of reference indicate the same part, in the several figures.

30 My invention relates to those machines, for removing the bark from willow or other twigs commonly used in basket making, in which the said twigs are rubbed or rolled between elastic surfaces for the purpose of loosening the bark; and my invention consists in the peculiar form and arrangement of the vibrating yielding surfaces whereby the bark is more effectually loosened upon the varying sizes of twigs; also in an independent self operating feeding device, for presenting fresh and different parts of the twigs to the action of the rubbing surfaces; and a self operating raking or scraping apparatus for removing the loosened bark 35 from the twigs, together with certain peculiarly formed guides to keep in place the twigs in their passage through the machine; the whole forming an automatic machine capable of producing more uniform and better results than those machines now in use.

40

To enable others to make and use my invention, I will proceed to describe its construction and operation.

A is a bed-plate supported at convenient 55 height upon legs B B B B B; at one end of

this bed-plate is the main or driving shaft C, supported in suitable bearings. On the shaft C, are secured three eccentric wheels a' a^2 a^3 ; two of these eccentrics (a' and a^3) are connected to and give a reciprocating motion to the lower rubbing slab H by means of the connecting rods b' b^3 , while the other or middle eccentric a^2 , is connected to the upper rubbing slab, J, by the connecting rod b^2 , and is fixed upon the shaft C, in such relative position to the eccentrics a' , and a^3 , as to give to the said rubbing slab J, a reciprocating motion opposite to that of the slab H. Below, and nearly under the edge of the bed-plate is a shaft D, having its axis 60 at a right angle with that of the driving shaft C. This shaft D, is connected to, and receives a motion reduced to one fourth of that of the driving shaft C, by means of the train of toothed wheels c' , c^2 , c^3 , c^4 , c^5 , c^6 , 65 two of which wheels c^3 , c^4 , are right angled bevel wheels. Upon the shaft D, are secured four cams d' , d^2 , d^3 , d^4 .

E', and E^2 , are two upright frames rising 70 from the bed-plate A, and firmly fastened thereto. These frames E', E^2 , are connected at the top by two cross-bars F', F^2 , and at the bottom by two rods G', G^2 ; these rods serve also as supports and guides for the lower rubbing slab H. This rubbing slab (H) is formed of a thick plate of india-rubber e' , let into or otherwise firmly fastened to a plate of metal e^2 ; on the bottom of this plate (e^2) are four lugs or projections e^3 , e^3 , e^3 , e^3 (Fig. 8) bored out to slide on the rods G', G^2 . Two joints e^4 , e^4 , serve 75 for the attachment of the connecting-rods b' , b^3 , before mentioned.

The upper rubbing slab J, is constructed 80 as follows; of a rectangular frame 1 divided longitudinally into three compartments by two ribs 2, 2 , equal in depth to the sides of the frame. To the frame 1 is secured a cover 3, which has its upper surface formed 85 into recesses for the reception of water; and holes 4, through the bottoms of said recesses admit the water to the interior of the frame 1. From each end of the frame 1, rises a lug or stirrup 5, by which the frame 90 is suspended, as hereafter described; and at one end of the said frame 1, is a joint 6, for the attachment of the connecting rod b^2 , before described. The compartments in the frame 1, are filled with small blocks 7, of 95 the form represented in Fig. 7, said blocks 100 105 110

being guided in and prevented from falling out of the frame 1 by projections on the sides of the blocks 7, fitting into recesses 8, extending from the top nearly to the bottom of the sides and ribs 2, of the frame. The blocks 7 are pressed upon by annular springs 9, which bear against the cover 3, of the frame; and the said blocks (7,) are rounded at their lower ends, and fluted, which ends project below the bottom of the frame 1, and together form an undulating fluted surface capable of yielding and accommodating itself to the twigs of different sizes which may be pressed between the rubbing slabs, and as the undulations of the said surface are made shorter than the vibrating motion of the slab J, the larger twigs will at times be rolled into and lie in the hollows thus permitting the high, or more projecting portions of the surface, to act upon the small twigs; thereby insuring the more perfect loosening of the bark of all the twigs which may be between the rubbing slabs, even if said twigs vary greatly in size. The finer flutings of the blocks 7, are to indent the bark that it may be the more readily loosened.

The rubbing slab J, constructed as above described, is suspended immediately over the slab H by the lugs 5, from a rod I, which rod passes through a slot in each of the upright frames E', E². To the ends of the rod I are attached two connecting links or rods g', g², the lower ends of which are jointed to two levers h³, h⁴, at or near the centers of the length of said levers; these levers have their fulcra at the end and are jointed to the bed plate A; their other and opposite ends rest upon the cams d', d²; these cams are so formed as to raise the rubbing slab J, high enough to allow the largest twigs to pass easily between the two slabs. One eighth of the revolution of the cams d', d², is employed in so raising said slab (J,) and the slab J, remains in such raised position during another eighth part of the revolution of the cams d', d², when it is allowed to descend somewhat more rapidly than it was raised. Pressure is applied to the twigs when between the rubbing slabs, by a weight K, acting through a divided lever L, which is hung by one end to the cross bar F and has at f, a transverse axle bearing at each end a friction wheel f'; these friction wheels rest on the top of the rubbing slab J.

Just above the surface of the bed plate and on the sides of the frames E', E², and of the short posts M, are four guides N, N, N, N, in which slide the sides of the feeding frame or carriage, which is constructed as follows:

h', h², are two side pieces which are connected to each other at each end by a plate 15 of metal i' or i² bearing upon its upper sur-

face a thick plate of india-rubber or other yielding and elastic material. From each side piece rise two short uprights to the ends j', j², of which are jointed two levers k', k², said levers being there suspended near their 70 centers. The outer ends of these levers k', k², terminate over the ends of the plates i', i², while their other or inner ends, curving upward, pass each other and lie under a roll on and near the end of the rod I. 75 The outer end of each of these levers is connected to the end of the corresponding lever on the opposite side piece, h', by a plate of metal l', l², similar to and immediately over the plate i', i², connecting the ends of 80 the side pieces h', h²; this plate l', l², has on its under surface a plate of india-rubber secured thereto, and forms with the plate i', i², a pair of jaws with elastic surfaces. The weight of the plates l', l², keep the inner ends 85 of the levers k', k', k², k², pressed up against the rolls on the rod J, and when said rod (J) is raised, as before described, the plates l', l², descend upon their mates i', i², firmly clasping the willow twigs which may lie 90 between them.

From the front ends of the side pieces h', h², curved prongs m', m² pass downward, and backward, having at their ends rolls m³, m⁴, which are kept bearing against the cams 95 d', d², by means of two spiral springs m⁵, m⁶; said springs are secured to the bed plate A, and act upon a cross bar, m⁷, which forms part of the feeding carriage. By means of the aforesaid springs (m⁵, m⁶), and cams, 100 (d³, d⁴), the feeding carriage receives an occasional motion backward and forward; and the cams d³, d⁴, are so shaped and are placed on the shaft D, in such relation to the cams d', d², that when the rod I (carrying the 105 slab J) is raised to its full height, the feeding carriage will commence its forward motion, and will have completed that motion just before the rubbing slab J, commences its descent. The feeding carriage remains 110 in its advanced position until after the rubbing block J, has completed its descent, when it (the feeding carriage) returns to its first position. In Figs. 1, and 3, the feeding carriage is represented in its most advanced 115 position, and the rubbing slab J, as having commenced its descent. The upper surfaces of the lower jaws i', i², of the feeding carriage are level with the upper surface of the slab H. Behind the jaws i', l, i², l², and secured to the backs of said jaws are strips n, of thin sheet metal, so bent as to form flaring guides to facilitate the introduction of the twigs between the jaws. Similar flaring guides are placed just behind the two rubbing slabs 120 H, J, (marked n² in Figs. 2 and 3) and are secured to the two short posts M, M.

Just in front of the rubbing slab H and secured to the frames E', E², is a rake or scraper O of sheet metal with pointed and 130

wedge shaped teeth formed in its upper edge; the centers of these teeth are about level with the top of the rubbing slab H. In front of the ends of the rake O, are two perpendicular rods o' , o' , connected at the top by a cross piece o^2 ; these rods are guided in projections formed on the front edges of the frames E', E². To the backs of the rods o' , o' , is secured a rake P, formed like O, and placed far enough forward to pass readily down in front of the rake O; the teeth of the upper rake P are over those of the lower rake O. The rake P is held up against a stop p^1 , at each end, by two spiral springs p^2 , p^2 , which are secured to the cross bar F². On the tops of the frames E', E², are bearings for a small shaft Q lying parallel with the shaft D (under the bed plate). This shaft Q projects some distance beyond its bearing 20 at one end and has secured to that end an arm R¹, carrying at its extremity a weight R². On this shaft Q and between its bearings are two small arms or pawls q', q², the extreme ends of which are immediately over 25 the cross piece o^2 , of the rods bearing the rake P. From the side of the pawl q' projects a pin q³, which rests on a corresponding pin q⁴, projecting from the side of a lever r'. This lever r', is hinged to the 30 frame E', and continuing downward terminates just below the top of the side piece h', of the feeding carriage. A spiral spring r², keeps the lever r, in position against the stop r³, projecting from the frame E'. Thus the 35 weight R², is supported, in the position shown in the drawings, by the lever r', when said lever is in position against the stop r³.

On the inside of the side piece h', of the feeding carriage is a small spring catch s, (Fig. 3) chamfered at its end but having a square edge in front. This catch s, is so placed that, when the feeding carriage moves back, the chamfered end of the said catch shall pass under the end of the lever r' (being wedged down in so passing) and shall snap up behind the end of the said lever, when the carriage shall have completed its backward motion; but when the carriage again moves forward the end of the lever r' 50 will be pulled forward until it draws off from the catch s, when it will fly back against the stop r³.

From the top of the frame E', projects a stout pin or stud S on which turns a cogged wheel T' having a long hub with a pulley T² on its end. The pulley T² and gear T' receive motion (in the direction indicated by the small arrow in Fig. 3) by means of a belt or its equivalent which passes around 55 a small pulley T³, fastened to the end of the shaft D.

Secured to the shaft Q, and in position to mesh with the cogged wheel T', is another cogged wheel U; a number of the teeth of 60 this wheel (U,) are cut away, and in such

part of the wheel that if the shaft Q were turned in the direction indicated by the large arrow in Fig. 3, the wheels U and T' would come into mesh when the weight R², had nearly reached its lowest point, and said 70 wheels would run out of mesh just before the shaft (and weight) had reached the position shown in the drawings.

At the ends of the upper rake P are two fastening pieces extending down and holding in place a shelf or guide of sheet metal t, which is between the lower rake O, and rubbing slab H, and is nearly level with the top of the rake O, when the upper rake P, is 75 against its stops.

The machine being driven by a belt running over the pulley V on the main shaft, and starting from the condition of its parts as indicated in the drawings, its action, and operation on the willow twigs presented to 80 it will be as follows. The eccentrics a' a² a³ will impart to the two rubbing slabs H, and J, a rapidly reciprocating motion, the said slabs being guided and sliding on the rods G' G² and I, the motion of the one slab being always in a direction opposite to that of the other. The rubbing slab J, will descend, by reason of the revolution of the cams d', d², until its surface nearly touches that of the slab H; the jaws i', l', and i², l², 85 of the feeding carriage will consequently be opened (by the lifting of the jaws l', l²); the feeding carriage will now move back, by the action of the springs m⁵, m⁶, and cams d³, d⁴, (as described), the jaws l', l², remaining 90 lifted, and the spring catch s, will snap up behind the end of the lever r'. The machine being in this condition, a number of the twigs to be peeled are thrust between the jaws i', l', of the feeding carriage and are 95 pushed forward through the guides n², n², until the ends nearly touch the edges of the rubbing slabs; by the time sufficient number of twigs can be so introduced, the upper slab J, will commence to rise and the jaw l', 100 will in consequence descend upon the twigs, clasping them tightly, the elastic surfaces of the jaws yielding and accommodating themselves to the varying sizes of the twigs. The feeding carriage will not run forward, 105 carrying the twigs and introducing their ends between the rubbing slabs H and J. The spring catch s, will draw forward the end of the lever r', and will thus remove the pin q⁴, from under the pin q³; the weight R² being thus unsupported will press (through the pawls q', q²) upon the cross piece o² of the rods o', o', and being adjusted so as to 110 preponderate over the sustaining power of the springs p², p², the said weight will press down the rake P until the teeth of said rake shall have passed below the teeth of the rake O, at which point, the ends of the pawls q, q, will, by their departure from a tangent line, be drawn off from the cross-

115

120

125

130

piece o^2 , and the rake P will spring up against its stops. The weight R^2 will continue to fall until the teeth of the wheel U , are brought into mesh with those of the wheel T' , when the said weight will be carried around in the direction indicated by the large arrow (in Fig. 3) until brought into such position that the running out of mesh of the wheels U , and T , will allow the weight R^2 , to be again supported by the pin q^4 in the end of the lever r' , which lever will have returned to its first position in the manner hereinbefore described.

The feeding carriage having completed its forward motion, the slab J , will descend upon the portion of the twigs lying under it, and such portion of the twigs as may thus be between the rubbing slabs are then submitted to their rolling rubbing and indenting action; the action of the upper slab J , upon the twigs being substantially such as hereinbefore described, and the yielding nature of the surface of the lower slab H affording additional compensation for the varying sizes of the twigs. Water is kept continually flowing upon the cover of the upper slab (J), and finding its way through the holes in said cover and between the blocks (7,) contained in the slab (J), moistens the portion of the twigs being rubbed, and softening the bark, greatly facilitates its removal. After the slab J , has fully descended upon the twigs, the feeding carriage will run back; and the rubbing slabs, having made a number of vibrations, the upper one (J), will rise, and the feeding carriage again running forward will introduce a fresh portion of the twigs between the rubbing slabs. At the commencement of this forward motion of the feeding carriage, the rake P , will perform its descent as before, accomplishing this and again springing up, before the carriage has moved forward far enough to bring the ends of the twigs under the said rake; but at the termination of this forward motion of the feeding carriage, the ends of the twigs will lie over the edge of the lower rake, far enough to enter between the forward jaws i^2 , l^2 , of the carriage, when it again moves back, which it will do after the slab J , has once more descended upon the twigs. Upon the next forward motion of the feeding carriage, the front jaws i^2 , l^2 , will be closed upon the front ends of the twigs; and the rake P , will commence its descent as before, but will be arrested by the twigs lying under it, and will remain pressed down upon said twigs, which are wedged in the angular recesses between the teeth of the two rakes P , and O , and being drawn forward by the jaws i^2 , l^2 , are stripped of the bark previously loosened by the action of the rubbing slabs. The motions of the feeding carriage and rubbing slabs

continue as before; successive portions of the twigs being submitted, first to the action of the slabs (J , and H), and then drawn through the teeth of the rakes (P , and O), by each motion of the feeding carriage. 70 When the whole length of the longest twigs has thus been drawn through the rakes, the rake P , being no longer supported, is carried down until the ends of the pawls q' , q^2 , slip off from the cross bar o^2 , when its action 75 and that of the weight R^2 will be as hereinbefore described, the whole machine being in condition as at first. It will be seen that a continual supply of twigs will insure a continued action of the machine as above 80 described.

I am aware that yielding and elastic surfaces vibrating in opposite directions have been employed for the loosening of the bark of willow twigs; but said surfaces have 85 both been of india rubber or other homogeneous material continuous in itself, and have been in form curved, being the surfaces of rollers vibrating in the direction of their axes; their surfaces being so curved 90 presented but little surface to the action upon the twigs, and were thus liable to rapid wear. I am also aware that an automatic feeding of the twigs to the action of the rubbing surfaces, has been accomplished 95 by a rotation of the vibrating rollers above mentioned; but such feeding occurs during the time that the pressure of the rubbing surfaces is upon the said twigs which pressure being very great causes much wear to 100 the bearings of the rolls and the mechanism for giving them motion. I therefore do not claim the use of vibrating yielding surfaces for the purpose of loosening the bark of twigs; nor do I claim an automatic feeding device when said feeding device acts to move the twigs during the action of the rubbing surfaces upon the twigs. 105

I do not claim the use of a picking device for removing the loosened bark from 110 the twigs, as such device has been employed by others.

What I claim as my invention, and desire to secure by Letters Patent, is—

1. A rubbing slab having its acting surface of undulating form, as described, the said surface being formed of yielding segments; the whole being constructed substantially as herein before described and for the purpose specified. 115

2. The rubbing slab H , having a flat elastic and yielding surface, acting in combination with another properly formed slab, and a feeding device acting substantially as herein specified. 120

3. Receptacles for water forming part of the rubbing slab, as described.

4. Giving to the rubbing slabs or one of them a motion, at times, and by means of the cams d , d , or their equivalents, which 130

shall separate the two slabs and prevent their action upon the twigs while the twigs are moved for the purpose of feeding.

5. A yielding clamping surface in combination with another surface, the said surfaces acting in combination with a separate rubbing device; when the said clamping surfaces act to feed the twigs substantially in the manner described.
- 10 6. The mode substantially as hereinbefore specified of presenting different portions of the twigs to the action of the rubbing surfaces; its characteristics being, that the twigs are moved by the feeding device dur-

ing the time when the pressure of the rubbing surfaces upon the twigs is relieved; 15 and that the feeding device ceases to act upon the twigs at a time when the pressure of the rubbing surfaces is upon the twigs.

7. In combination with a rubbing mechanism for loosening the bark, and a feeding device, an automatic raking or scraping device constructed substantially in the manner described and for the purpose specified.
